CASCADE AMPLIFIER USING TRANSFORMER COUPLING BETWEEN THERMIONIC-VACUUM TUBES.

Application filed November 30, 1927. Serial No. 236,798.

When constructing cascade amplifiers it is customary to introduce means for preventing the development of uncontrolled feed-backs which would result in poor general operation. Toward this end most modern amplifiers of two or more stages are enclosed in metal housings which often take the form of a "catacomb", i. e. a box divided into compartments, into each of which 10 is fitted the coil or in some cases the whole stage including the tube and associated tuned circuit.

This practice is quite common particularly in the case of superheterodyne receivers wherein the intermediate wave amplifier is enclosed wholly or in part within a shielding catacomb. Such amplifiers are generally operative on a fixed frequency and are tuned, as to each stage, once and for all, at 20 the factory. It is very important that these stages be accurately tuned, and that the amount of feed back with its resultant regenerative effect toward greater amplification be under complete control so as to be neither 25 so great as to cause unstable operation or so little as to result in poor efficiency.

To construct an amplifier that will have just enough interstage coupling and at the same time have accurately tuned stages so 30 as to produce a relatively ideal result, is a simple laboratory operation but becomes extremely difficult of duplication on a factory production basis.

For example, when winding a large number of inductance coils for operation in, say, a four stage type of amplifier tuned for operation at a fixed frequency of, say, 192.5 kilocycles, there are many things that must be watched.

40 1. The coil formers must all be of exactly the same size.

2. The coils must all have exactly the same number of turns.

45 3. Care must be taken when placing the coils in the catacombs to have them accurately placed and to wire them up to accessory apparatus in such a way that no conditions can obtain in one section or stage that are not duplicated exactly in all stages of the cascade.

50 4. The wire used must be of absolutely uniform gauge and the insulation on the wire, or between turns and layers must be of ab-

solutely uniform quality and thickness. The resistance per foot of the wire must not vary 55 at all.

If all these conditions could be met in production it would not be necessary to resort to any dodges to effect the development of satisfactory amplifiers on a commercial 60 basis. The first three of these conditions can be met satisfactorily but the fourth condition cannot. It is not possible at this time to make inductance coils anywhere nearly 65 alike, due principally to variations in gauge of the wire and in thickness of insulation. Nor can coils be "matched" to a sufficient degree of accuracy by any method now known so that when placed in service they will function without at least some adjustment. The primary purpose of this invention is to provide cheaply a means for quickly 70 making the necessary final slight adjustment to regulate feed back and to effect perfect tuning after the amplifying device has 75 been actually placed in operation.

We attain our object by providing a cellular metal shield with a movable metal cover constructed and arranged so that the air gaps between the cover and the division walls of 80 the cells may be varied to vary the feed back from coil to coil, and so that the tuning of individual amplifiers may be adjusted by varying the distance of the cover from the inductance of the amplifier.

85 The invention is illustrated in the accompanying drawings in which

Fig. 1 is a longitudinal section of a metal shield formed with five cells; and

Fig. 2 a cross section of the same.

In the drawings like numerals of reference 90 indicate corresponding parts in the different figures.

In the embodiment of the invention illustrated a copper shield 1 of box-like form is 95 divided by partitions 2 into five cells intended to hold five closely alike but slightly different transformers intended to function on the same wave length. The closing cover 3 for this cellular shield, if made flat and set close to the partitions, would completely "lock-up" the inductances so that there would be practically no magnetic feed-back from one to another at ordinarily used frequencies.

We have, however, made this top cover of 105 a sheet of flexible metal of springy quality

and of an arched form. This cover when set in place and supported by its edges allows an air-gap to exist between adjoining cells of the shield and so permits considerable feed-back between the coils. Ordinarily the cover will rest on the partitions as shown.

A means is then provided for varying these air-gaps. A heavy bar 4 extending lengthwise along the centre of the cover is held at its 10 ends by threaded legs extending down through the cover and through the bottom of the shield and movable from points outside the latter. Usually the ends of the legs will be threaded and nuts 5 screwed thereon. By turning the nuts on these legs, thus 15 moving them up or down, the cover can be more or less flexed one way or the other so as to open or close the air-gaps.

In addition to this a further effect is produced. When an inductance is enclosed within 20 a metal casing its electrical characteristics at high frequency are somewhat affected by the distances of the metal walls from the sides and ends of the coil. In other words, 25 if we move one of the box-sides nearer to or farther from the coil a tuning effect will result. Use is made of this phenomenon when the curved cover of the shield is adjusted. If one end of the cover is pulled down closer 30 than the other, a gradient tuning of the cascade can be effected. It is observed that the combination of this gradient tuning, and the similarly graded variation of the inter-cell 35 air-gaps gives an almost unlimited combination of tuning adjustments within narrow limits. Thus by juggling the two adjusting nuts on the bottom of the shield an experienced operator can obtain perfect cascading of an intermediate amplifier.

40 For the passage of connecting wires the sides of the cover are provided with notches 6.

The original area of the air-gap will vary in different designs as it depends upon coil 45 characteristics and will be larger in large shields enclosing small coils than in small shields enclosing large coils. It will be smaller when coils operate at high frequencies, and will be larger when used with coils operating at comparatively low frequencies.

50 It must be clearly understood that the constructions described will usually be of value only, when the coils are matched within narrow limits, as the adjustment effected by varying the position of the cover is very fine 55 and itself operates over very narrow limits in ordinary practice.

With mechanical modifications this arrangement could also be applied to cascade amplifiers of the "tuned radio frequency" 60 type.

What we claim as our invention is:

1. A metal shield for cascade amplifiers using transformer coupling comprising a plurality of open topped cells arranged side

by side and separated by a partition wall or 65 walls; a cover for the cells held in spaced relationship to the partition; and means for varying the position of the cover relative to the partition to vary the air-gap between the cover and the partition.

2. A metal shield for cascade amplifiers using transformer coupling comprising a plurality of open topped cells arranged side by side and separated by a partition wall or 70 walls; a flexible cover for the cells held in spaced relationship to the partition; and means for flexing the cover to vary the air-gap between the cover and the partition.

3. A metal shield for cascade amplifiers using transformer coupling comprising a box 75 divided into a plurality of cells by a plurality of partitions; a transversely arched flexible metal plate supported by its edges over the partitions so as to leave air gaps between its under surface and the partitions; and means 80 for flexing the cover to vary the air-gaps between the cover and the partitions.

4. A metal shield for cascade amplifiers using transformer coupling comprising a box 85 divided into a plurality of cells by a plurality of partitions; a transversely arched flexible metal plate supported by its edges over the partitions so as to leave air gaps between its under surface and the partitions; and means 90 for flexing the cover to vary the air-gaps between the cover and the partitions comprising a bar engaging the back of the flexible cover, and means engaging the bar adjacent opposite ends to move it to flex the cover.

5. A metal shield for cascade amplifiers 95 using transformer coupling comprising a box divided into a plurality of cells by a plurality of partitions; a transversely arched flexible metal plate supported by its edges over the partitions so as to leave air-gaps between its under surface and the partitions; and means 100 for flexing the cover to vary the air-gaps between the cover and the partitions comprising a bar engaging the back of the flexible cover, and means engaging the bar adjacent opposite ends to move it to flex the cover.

6. A metal shield for cascade amplifiers 105 using transformer coupling comprising a plurality of open topped cells arranged side by side and separated by a partition wall or walls; a cover for the cells held in spaced relationship to the partition, the edges of the cover being notched to provide openings for 110 the passage of connecting wires; and means for varying the position of the cover relative to the partition to vary the air-gap between the cover and the partition.

Signed at Toronto, Can. this 15th day of 115 November 1927.
